UNITED STATES PATENT OFFICE.

ALBERT R. WILLIAMS, OF IRENTON, OHIO, ASSIGNOR TO THE IRENTON ENGINE COMPANY, OF IRENTON, OHIO, A CORPORATION OF OHIO.

CONTROLLER LOCK-LEVER.

1,385,935.

Specification of Letters Patent.

Patented July 26, 1921.

Application filed July 15, 1920. Serial No. 396,439.

To all whom it may concern:

Be it known that I, ALBERT R. WILLIAMS, a citizen of the United States, residing at Ironton, in the county of Lawrence and State of Ohio, have invented certain new and useful Improvements in Controller Lock-Levers, of which the following is a specification.

This invention relates to a controlling lock lever for limiting the range of movement of the controller or switch lever of electric controllers or switches and for locking the controller or switch lever in certain fixed positions.

Controllers of the above indicated type are usually provided with a control handle and lever, and it has been found possible for the operator to hold the latch or lock open and pass the neutral or stop position 20 and thereby reverse the current suddenly, which sudden reversal of the electric current causes excessive arcing at the contact segments and fingers which not only damages said segments and fingers, but also 25 the mechanical parts of the electric motor or machine which it controls and operates.

The objects of my invention are to provide a controller or switch lever operating the contact segments or fingers with coacting means, so that the controller or switch 30 will be limited in its range of operations or may be locked in certain fixed positions and become fool proof and avoid all possibility of sudden reversal of current, excessive arcing at the contact segments or 35 fingers, or injury to the motor for reasons above indicated.

A further object of the invention is to provide a combination and arrangement of 40 elements which consists of few parts, can be easily manufactured, installed, or taken apart and inspected, and repaired at a minimum of cost.

Further objects and advantages of the 45 invention will appear from the detailed description of the parts and mode of operation of the device to be hereinafter more fully given.

The invention consists of structural characteristics and relative arrangements of elements to be hereinafter more fully described and particularly pointed out in the appended claims.

In the drawings, in which similar refer-

ence characters indicate the same parts in 55 the several figures,

Figure 1, is a plan view of a controller top showing the lever in neutral or off position;

Fig. 2, is a longitudinal section on line 60 II-II, of Fig. 1;

Fig. 3 is a plan view similar to Fig. 1, showing the lever between neutral and full position in one direction and controller lock lever in an arc of operation, and 65

Fig. 4 is a section on line IV-IV of Fig. 2.

Referring to the drawings, 10 is the usual controller top or cover provided with stop lugs 11 and 12 preferably cast integral 70 therewith, and having an opening 13 adapted to receive and through which passes the rotatable controller shaft 14 carrying on its inner section, contact segments 15 and 16 which engage the usual contact fingers 17, 75 for purpose of reversal of current, and segments 18 and 19 for varying the speed of the motor, as is common in this class of inventions and need no further description.

The top 10 of the controller is provided 80 with a section or surface 20 on which a lock lever 21 oscillates or operates, said lever 20 being pivotally connected on said surface 20 by a threaded pin 22 engaging a threaded opening 23 in the top 10, as 85 shown. Lock lever 21 is provided on its upper or outer side with three lugs or bosses 24, 25, or 26, and a projection or extension 27, said lugs or bosses 24 and 25 act as stops for purposes to be presently described, 90 while lug 26 is drilled from its bottom or under face to form a circular recess to receive a small coil spring 28 and plunger 29, said plunger 29 being adapted to be seated in any one of three pockets 30, properly spaced and arranged to register with the three different adjusted positions of the lock lever 21.

Mounted on the controller shaft 14 is an index collar 31 and a controller lever 32, 100 said controller lever 32 being firmly secured to said shaft 14, and the index collar 31 attached and rotating with the lever 32, so that the shaft 14, lever 32 and collar 31 will rotate in unison during the rotation or adjustment of controller segments 15, 16, 18 and 19.

The index collar 31, is provided with a

concave recess 33 in its periphery, into which the projection or extension 27 on lock lever 21 will swing when the controller lever 32 is in the neutral position, as shown in Figs. 1 and 2. The underside of the controller lever 32 is provided with a depending lug 34 which is so arranged and constructed to abut against the stop lugs 11 and 12, on top or cover 10, and lugs or bosses 24 and 25, depending upon the adjusted position of the lock lever 21, for purposes to be presently described.

The parts being constructed and arranged as described, the operation of the invention is as follows:

Referring to Figs. 1 and 2, it will be seen that the controller lever 32 is locked in the neutral or off position in view of the fact that the depending lug 34 on said lever 32 is between and practically in contact with the lugs or bosses 24 and 25 of the lock lever 21 and the projection or extension 27 on said lock lever 21 is within the concave recess 33 of index collar 31, and hence it will be impossible to move the controller lever 32 out of this neutral or off position until the lock lever 21 has been thrown into the position shown in Fig. 3 against the stop lug 12, or in the opposite direction from that shown against the other lug 12. When the lock lever 21 is thrown in the position shown in Fig. 3, the controller lever 32 is limited in its oscillating movement or adjustment between the stop lug 11 on cover 10 and the lug or boss 25 on lock lever 21, and when the lock lever 21 is thrown in the other position from that shown in Fig. 3, the controller lever 32 is limited in its movement between the other stop lug 11 and the lug or boss 24 of lock lever 21, as will be readily understood.

From these described arrangements, relations and co-operation of the parts, it will be seen that the lock lever 21 cannot be thrown into its central position, due to interference between the projection or extension 27 on lock lever 21 and the periphery of index collar 31 until the controller lever 32 has been brought to its neutral or off position, as shown in Figs. 1 and 2, and the concave recess 33 is so positioned as will enable said projection or extension 27 to clear the edge of the index collar 31; when if desired the lock lever 21 may be secured to its central position and locking the controller lever 32 between the lugs or bosses 24 and 25, as heretofore explained. Similar and reverse operations can be effected and will be manifest when the controller lever 32 is turned in the reverse direction and is between the stop lug 11 and the lug or boss 24.

From the foregoing disclosure of operation, the controller lever 32 is unable to be thrown from one side or direction of operation to the reverse side or direction without

coming to a full stop, thereby absolutely preventing the sudden reversal of the current through the motor or excessive arcing at the contact segments and fingers of the controller.

It will also be clear that the lock lever 21 has another and most important function of being able to positively lock the controller lever 32 in a fixed or neutral position.

In the vertical position of the controller 75 casing or shaft 14, it is not essential to provide the lock lever 21 with the boss 26, coil spring 28, and plunger 29 co-operating with the pockets 30, and is only shown in the present instance, should it be desired to hold the 80 lock lever 21 in any one of its three adjusted positions in case the controller or shaft 14 is horizontal or inclined from an upright position.

From the foregoing disclosure of construction and operation of the device, it will be apparent that all the objects and advantages recited in the statement of invention have been fully and efficiently carried out in a simple manner, and while I have described the invention with more or less minuteness as to the details of construction and arrangement, the same is not limited to this particular and preferred form shown and described, and many modifications will readily suggest themselves to any one without departing from the spirit of the present invention and be within the scope of the claims.

What I claim is:—

1. A controller or switch operating device comprising a cover having an opening, a rotatable shaft passing through said opening of the cover, a controller lever secured to said shaft for rotating the same, a collar rotating with said shaft and controller lever, a lock lever pivotally supported on said cover in proximity to said controller lever and collar, means on said lock lever to engage said controller lever and limit its angle 100 and direction of rotation, and a secondary means on said lock lever to engage the index collar to lock the controller lever in a fixed or neutral position.

2. A controller or switch operating device 115 comprising a cover having an opening, a rotatable shaft passing through said opening of the cover, a controller lever secured to said shaft for rotating the same, an index collar rotating with said shaft and controller 120 lever, a lock lever pivotally supported on said cover in proximity to said controller lever and collar, lugs on said lock lever to engage said controller lever and limit its angle and direction of rotation, a projection on said lock lever to engage the index collar to lock the controller lever in a fixed or neutral position, and stops on said cover for limiting the movement of said controller 125 lever and lock lever.

3. A controller or switch operating device comprising a cover having an opening, a rotatable shaft passing through said opening of the cover, a controller lever secured 5 to said shaft for rotating the same, an index collar rotating with said shaft and controller lever and provided with a recessed section at its periphery, a lock lever pivotally supported on said cover in proximity to said 10 controller lever and collar, lugs on said lock lever to engage said controller lever and limit its angle and direction of rotation, and a projection on said lock lever adapted to pass into the recessed section of and inter- 15 engage the index collar to lock the controller lever in a fixed or neutral position.
4. A controller or switch operating device comprising a cover having an opening, a rotatable shaft passing through said opening 20 of the cover, a controller lever provided with a depending lug and secured to said shaft for rotating the same, an index collar rotating with said shaft and controller lever and provided with a recessed section at per- 25 ipherity, a lock lever pivotally supported on said cover in proximity to said controller lever and collar, lugs on said lock lever to
- engage the depending lug on said controller lever and limit its angle and direction of rotation, a projection on said lock lever 30 adapted to pass into the recessed section of and interengage the index collar to lock the controller lever in a fixed or neutral position, and stops on said cover for limiting the movement of said controller lever and 35 lock lever.
5. A controller or switch operating device comprising a cover having an opening, a rotatable shaft passing through said opening of the cover, a controller lever secured 40 to said shaft for rotating the same, locking means connected to and rotating with said controller lever, a movable lock lever supported on said cover in proximity to said controller lever, means on said lock lever to 45 engage said controller lever and limit its angle and direction of rotation, and means on said lock lever to engage the locking means connected to the controller lever to lock the controller lever in a fixed or neutral 50 position.

In testimony whereof I affix my signature.

ALBERT R. WILLIAMS.
